DAVID W. BROOKS, OF NEW YORK, N. Y., ASSIGNOR TO CONCRETE STEEL COMPANY, OF NEW YORK, N. Y., A CORPORATION OF DELAWARE.

FACING-BAR FOR CONCRETE STRUCTURES.

1,244,831.

Specification of Letters Patent. Patented Oct. 30, 1917.

Application filed December 19, 1913. Serial No. 807,576.

To all whom it may concern:

Be it known that I, DAVID W. BROOKS, a citizen of the United States of America, residing in New York city, borough of Manhattan, and the State of New York, have invented an Improvement in Facing-Bars for Concrete Structures, of which the following description, in connection with the accompanying drawings, is a specification, like 10 letters on the drawings representing like parts.

The present invention relates to improvements in facing bars for use with concrete, these bars being designed to protect the corners of concrete structures and other surfaces thereof ordinarily subject to wear. The object is to provide a covering for the edge or other wearing surface which will effectually prevent abrasion and will further 20 protect the concrete from fracture by transmitting the impact of possible shocks into the body of the mass. A further object is to utilize the entire contents of iron bars of uniform or standard width to the utmost 25 advantage in providing anchorage facilities, or, in other words, so that facing bars having anchoring extensions of different lengths may be stamped from bars of the same width and thickness.

30 The above mentioned objects of this invention are accomplished by providing in such a bar a plurality of projections displaced at intervals from material along its edge to form anchoring members, the reach 35 of the said anchoring members being determined by their distances apart, as will be more readily understood from the drawings in which

40 Figure 1 is a perspective view showing a bar with its anchoring members in different stages of formation.

Fig. 2 shows in cross section the application of a bar to corners of a concrete structure, and,

45 Fig. 3 shows in perspective a similar construction wherein anchoring members are formed on both longitudinal edges of the bar.

In Fig. 1 of the drawings, a typical facing bar is shown with anchoring members in the positions, *a*, *b* and *c* to illustrate different stages in the formation thereof. The completed anchoring member *c* comprises 50 preferably a shank portion 1 having its base near the crest 6 of the bar and a headed por-

tion 2 having extensions 3, here shown as prongs which may serve as compression members acting upon the concrete lying between them to resist forces tending to move the bar outwardly. In forming such a member, it is stamped out of material forming the flange 4 of an ordinary angle iron or other iron of suitable cross sectional contour and thickness. The length of extension suitable for any given purpose is determined 60 by the length of the strip 5 of material cut from the edge of the flange 4. In this particular embodiment of the invention the prongs are formed by bending this strip into any suitable shape, as indicated at *b*, 65 and then the whole anchoring member may be displaced from the plane of flange 4 by pressing it inwardly as at *c*. From the foregoing it will be obvious that the length of the extension depends upon the distance between the members *a*, *b* and *c*, assuming that all the material in the bar is made use of. Shoulders 7 are formed at the base of each extension and the shank 1 may be provided 70 with lateral projections as 8 to give the anchoring member a more positive gripping surface in the concrete. In displacing these lateral projections downwardly, indentations 9 are formed in the flange 6, which, when the bar is embedded in concrete, as 75 in Fig. 3, present additional gripping surface tending to prevent the bar from shifting in the plane of its perforated flange.

It is contemplated that the parts herein described may be varied in length and shape 80 without departing from the spirit of the invention, as, for example, the length of the extensions in any given anchoring member may be different or they may be bent into dissimilar shapes. And it is also conceivable that the shape of the shank portion 85 may be varied from that herein described and illustrated, the essence of the invention being the provision, in a suitable metal bar, of a plurality of anchoring 90 members formed from the material thereof in such a way that their inwardly projecting extremities may be struck from material forming the edge of the said bar, varying 95 lengths of the same being produced by varying the distance between the said anchoring members.

I claim as my invention:—

A facing bar for concrete structures, comprising a facing member of substantially an- 100

110

gle iron form having punched-out portions at intervals along either or both webs, and anchoring members projecting inwardly from the facing member, one opposite each opening in the facing member, each of said anchoring members comprising a shank integral with the facing member and a pair of prongs diverging from the shank, the combined lengths of the two adjacent prongs 10 of any two adjacent anchoring members be-

ing substantially equal to the distance between the two corresponding openings in the web.

In testimony whereof, I have signed my name to this specification, in the presence of 15 two subscribing witnesses.

DAVID W. BROOKS.
